(Cl. D62—4)

To all whom it may concern:

Be it known that we, Arnold M. Wolf, Jerome L. Strauss and Jack Fairchild Fleming, citizens of the United States, have jointly invented a new, original, and ornamental Design for a Window Mounted Air Cooler Cabinet or Similar Article, of which the following is a specification, reference being had to the accompanying drawing, forming a part hereof.

Figure 1 is a front perspective view of a window mounted air cooler cabinet embodying our new design;

Figure 2 is a top plan view; and

Figure 3 is a fragmentary side elevational view thereof.

The essential features of our design reside in the portions shown in full lines.

We claim:

The ornamental design for a window mounted air cooler cabinet or similar article, substantially as shown and described.
